UNITED STATES PATENT OFFICE.

LEVIN FAUST, OF ROCKFORD, ILLINOIS.

LOCK.

SPECIFICATION forming part of Letters Patent No. 642,217, dated January 30, 1900.

Application filed July 14, 1899. Serial No. 723,831. (No model.)

To all whom it may concern:

Be it known that I, LEVIN FAUST, a citizen of the United States of America, residing at Rockford, in the county of Winnebago and State of Illinois, have invented certain new and useful Improvements in Locks, of which the following is a specification.

My invention relates to that class of locks which is known in the lock trade as "mortise-locks;" and it consists of certain new and useful features of construction and combinations of parts hereinafter fully described, and specifically pointed out in the claim.

Referring to the accompanying drawings, which form a part of this specification, Figures 1 and 2 are side views of counterpart plates that form the case of the lock. Figs. 3 and 4 are like views of the plate shown in Fig. 2, showing the operative parts of the lock arranged in operative position and relation thereon. Fig. 5 is an end view of the completed lock. Fig. 6 is an end view of a socket for receiving the bolt of the lock.

Like letters of reference indicate corresponding parts throughout the several views.

A B are counterpart plates having opposite recesses A' B' in the inner faces thereof and opposite recesses A² B² in the bottoms of the recesses A' B', one of such plates, B, being provided with a bolt-stopping lug B³, spring-supporting lugs B⁴ B⁵, and a keyhole B⁶.

C is a bolt adapted to be contained and slid in the recesses A' B' in the plates A B and provided with stopping-detents C' C² and an actuating-lug C³.

D is a curved spring confined endwise between the supporting-lugs B⁴ B⁵ on the plate B and holding the bolt C into engagement with the bolt-stopping lug B³.

E is a rivet securing the plates A B together.

F is a key which is inserted into the lock in such a manner that the bit thereof will enter the horizontal slot of the keyhole B⁶. After the same has been turned to the position shown in Fig. 4 it may be withdrawn, the bit thereof passing out of the vertical slot of such key-hole.

I claim—

In a lock, in combination, counterpart plates A B, having opposite recesses, A' B', in the inner faces thereof, and opposite recesses, A² B², in the bottoms of the recesses A' B', one of such plates being provided with a bolt-stopping lug, B³, spring-supporting lugs, B⁴ B⁵, and a keyhole B⁶, a bolt C, adapted to be contained and slid in the recesses, A' B', in the plates, A B, and provided with stopping-detents, C' C², and an actuating-lug C³, and a spring D confined endwise between the supporting-lugs, B⁴ B⁵, on the plate B, and holding the bolt C into engagement with the bolt-stopping lug B³, substantially as and for the purpose specified.

LEVIN FAUST.
